UNITED STATES PATENT OFFICE.

HARRY Y. ARMSTRONG, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

BANDING-MACHINE.

1,308,322.

Specification of Letters Patent. Patented July 1, 1919.

Original application filed October 7, 1915, Serial No. 54,646. Divided and this application filed May 17, 1918. Serial No. 235,168.

To all whom it may concern:

Be it known that I, HARRY Y. ARMSTRONG, a citizen of the United States, residing at Springfield, in the county of Hampden and 5 State of Massachusetts, have invented certain Improvements in Banding-Machines, of which the following description, in connection with the accompanying drawings, is a specification, like reference characters on 10 the drawings indicating like parts in the several figures.

This invention relates to packaging machines and will be herein disclosed as embodied in a machine designed especially to 15 fold bands, stamps, or the like around plugs of tobacco. It will be evident, however, that the various features of the invention are not limited to this particular use but may be also used in packaging or labeling cakes of 20 soap, chocolate, and other articles.

It is a common practice in the wrapping of articles of the general character above mentioned to affix a band or label to each package usually for the purpose of holding 25 in place the end folds of the wrapper in which the article is inclosed. Frequently this band also serves for certain ornamental purposes while in other instances, as in wrapping tobacco, the band usually is in the 30 form of a revenue stamp. In the latter cases reliability is an exceedingly important requirement of a machine by which the stamps are to be applied because of the expense involved in wasting stamps. In any case it is 35 desirable that the bands be firmly secured and neatly affixed to the packages. The present invention provides a banding mechanism designed to meet these requirements and in the specific form shown this mechanism is adapted to affix to each package both 40 a revenue stamp and also a band or label which may bear an attractive design or advertising matter.

In wrapping or banding many articles, 45 such as certain of those above mentioned, it is found that there is a very substantial variation in the sizes of the articles and that these variations are the cause of much trouble in performing the banding operations 50 especially where it is necessary to secure the band or similar device tightly about the package. It is an important object of

this invention to make provision for these variations and to devise a banding mechanism that will fold the bands tightly about 55 the packages and secure them in their folded positions.

The invention also is directed to other features including novel means for maintaining the bands in proper alignment during their 60 application to a package and for registering the ends of the bands accurately and to the provision of mechanism for performing the various operations on a wrapped package without tearing, or breaking, or wrinkling 65 the wrapper or the bands.

The manner in which it is proposed to accomplish these objects will be readily understood from the following description, reference being made to the accompanying drawings, in which,

Figures 1, 2 and 3 are angular views of a package showing the successive steps in the banding operation;

Fig. 4 is a vertical cross sectional view 75 showing a portion of the wrapping machine from which the packages are delivered to the banding mechanism provided by this invention and also showing a portion of the latter mechanism;

Fig. 5 is a vertical cross sectional view 80 through the banding mechanism, the plane of cut being substantially in the path of travel of the articles through the banding mechanism;

Fig. 6 is a fragmentary cross sectional view showing certain details of the banding mechanism;

Fig. 7 is a cross sectional view on the line 85 $x-x$, Fig. 5;

Fig. 8 is a vertical cross sectional view 90 through the band feeding mechanism;

Fig. 9 is a cross sectional view on the line 95 $9-9$, Fig. 8;

Fig. 10 is a fragmentary perspective view 100 showing certain details of the band feeding mechanism;

Fig. 11 is a vertical cross sectional view through the banding mechanism at right angles to the view shown at Fig. 5, certain of the parts being shown in front elevation, and

Fig. 12 is a plan view of the machine, partly in horizontal cross section, certain of

the parts being omitted for the sake of clearness.

The present application is a division of my copending application, Serial No. 54,646, filed October 7, 1915, for improvements in wrapping machines. The machine shown in that application was designed to wrap plugs of tobacco or similar articles one at a time in sheet wrapping material, a coupon 10 being inclosed in the wrapper with the tobacco, and then to fold about the package so produced two bands, one of which might consist of a revenue stamp and the other of a label bearing advertising matter. These 15 bands were folded over the end folds of the wrapper to secure them in their folded positions. The present application is concerned with the banding mechanism disclosed in the earlier application above designated.

20 The machine shown comprises a machine frame 2 having bearings in which a main shaft 4 is rotatably mounted and this shaft carries a handwheel 5 by means of which the machine may be operated manually, a loose 25 pulley 6 enabling the machine to be belted to any convenient source of power and a clutch by which a driving connection between the pulley 6 and the shaft 4 may be effected. A cross shaft 8 is driven through a bevel gear 30 connection with the main shaft 4.

Fig. 4 of the drawings shows a part of the mechanism of the wrapping machine including the tumble box 22, the folding chute 42 into which the packages are pushed by 35 the ejector 45, the final end folding operations being performed as the package is forced through the folding chute 42 by the ejector. This ejector carries each package completely through the folding chute on to 40 two ledges 48 that form continuations of the bottom of the folding chute into a position directly over a U-shaped plunger or elevator 50 which constitutes a part of the banding mechanism. The ledges 48 serve to secure 45 the package by its ends in position for the engagement therewith of the elevator 50. The plunger is mounted for vertical, reciprocating movement and carries the packages X one at a time to the devices that fold the 50 bands about the package. The operating mechanism for this plunger is best shown in Figs. 4 and 5 and comprises a lever 51 fulcrumed on the machine frame at 52 and having one arm connected by an adjustable link 55 53 with the shank 54 of the plunger which moves in vertical guideways, the other arm of said lever being provided with a roll which runs in a cam path formed in a cam 55 mounted fast on the cross shaft 8. As 60 clearly shown in Figs. 4 and 11, the left hand arm of the plunger 50 is pivoted to the other arm and is provided with a downwardly projecting extension which is acted upon by a spring 56 in a direction tending to 65 swing the upper end of the arm toward its

companion, this movement, however, being limited by a screw 57 that projects through the movable arm and is threaded into the shank 54. This arrangement is provided to enable the plunger or elevator to handle 70 packages varying in width. It will be evident from an inspection of Fig. 4 that the package is supported by the upper ends of the two elevator arms which for this purpose are notched or shouldered to provide 75 vertical beveled faces that engage the sides of the package and horizontal faces that engage the bottom of the package near its opposite sides. Since the ejector 45 has a stroke of definite length it will move the 80 rearward side of each package to a fixed point on each ejecting stroke. This stroke is so proportioned that the point just mentioned will be in line with the vertical package engaging face of the right hand arm of 85 the plunger 50, as the parts are seen in Fig. 4. Any variation in width of the package, therefore, will be accommodated by the yielding movement of the pivoted left hand arm, this movement being produced by the 90 contact of the beveled end of the arm with the side of the package when the elevator is raised.

While the package is supported on the two ledges 48 and just prior to the upward movement of the elevator 50 into engagement with the package, a band delivering mechanism operates to position two bands on the package in substantially the positions in which they are indicated at L and S, respectively, in Figs. 1 and 4. This band delivering mechanism comprises a double magazine 60 (see Figs. 8 and 12) designed to receive the stacks of labels and stamps, respectively, the stamps being separated from the 105 labels by a central partition. Two sets of stripper rolls 62, one set in advance of the other and both underlying the two stacks of bands, operate on the bottommost label and stamp to feed them forward simultaneously 110 into parallel guideways 63 and 64, respectively, which open in front of and at the bottom of the magazine. A pair of needles 74 project, respectively, into the two compartments of the magazine and prevent the 115 stripper rolls from advancing more than one stamp and one label at a time. The forward set of stripper rolls 62 is operated by driving connections with the cross shaft 8, these connections including a shaft 65, a 120 chain 66, and a gear 67 and the two sets of rolls are geared together by a train of gears 68 (see Fig. 12) so that they rotate together. Just as the bottommost label and stamp are advanced into their guideways 63 and 64, they are fed between two pairs of upper and lower rolls 69 and 70, respectively, (see Figs. 8 and 9) which are geared to each other and are driven by the gear 67. These rolls operate on the entire lengths of the two bands, 130

that is the stamp and label, to feed them forward in the guideways 63 and 64 and they are so positioned with reference to the length of the two bands that they advance them 5 until the forward ends of both bands lie at the forward ends of the guideways where they are positioned for the engagement of a nipper 72 which completes the band feeding operation. Narrow guides 73 overlie the 10 bands as they travel through their guideways 63 and 64 and prevent them from becoming displaced. The forward ends of these guides 73 are turned downwardly to insure the accurate positioning of the ends 15 of the bands.

When a package is pushed through the folding chute 42 by the ejector 45 and positioned over the elevator 50, it is forced between a pair of vertical plates 76 which lie 20 at opposite sides of the path of the package and are positioned to bear against the ends of the package and hold the end folds in place. These plates are supported loosely on pins 77 which are encircled by springs that 25 force the plates against the opposite ends of the package but permit them to yield outwardly when a package is forced between them. Both of these plates are apertured, as indicated at 78, Fig. 5, to permit the passage horizontally therethrough of the nipper 72. This nipper is reciprocated by means 30 of a bell crank lever 80 to one arm of which a cam follower 81 operated by a cam 82 fast on the shaft 4 is connected, and the other arm 35 of which is connected by an adjustable link 83 to the nipper bar, this bar being mounted to slide in a horizontal way 84 formed in a stationary part of the machine frame. The forward end of this nipper bar is shaped to 40 form the stationary jaw of the nipper. The movable jaw 85 is pivoted to the nipper bar at 86 and its rearmost end is pivoted to a block which slides in a channel bar 88 pivoted at 89 and normally held downwardly 45 by a spring 90. This spring thus acts to hold the nipper in its closed condition. A bell crank lever 92 pivoted on the machine frame at 93 and connected to the channel bar 88 by a link 94, carries a roll running on a surface cam 95 mounted fast on the shaft 4, which serves to open the nipper at the proper 50 points in its travel and allows the spring 90 to close the nipper at other points in its stroke.

55 The mechanism just described operates to advance the nipper 72 through the aperture 78 and over the elevator 50 to the forward ends of the band guideways 63 and 64, as shown in Fig. 10. At this time the cam 95 operates 60 through the connections just described to close the nipper on the two ends of the bands S and L, as shown in Fig. 10, after which the nipper immediately starts on its return stroke, thus drawing these two bands out of 65 their guideways and carrying them over

the package which at this time is resting on the two ledges 48 just above the elevator 50. As shown in Fig. 10, the nipper 72 carries two pins 96 which limit the entrance of the ends of the bands between the nipper jaws 70 and facilitate the accurate positioning of the bands on the package.

While the two bands S and L are being advanced to position them on the package they are moved over two glue applying rolls 75 one of which is shown at 97 (see Fig. 5) that rotate side by side in a reservoir 99 of glue or other adhesive and which apply a strip of glue to the entire length of both the label and stamp. These glue rolls may be driven in 80 any convenient manner but preferably are operated in the manner that the glue rolls are operated in the machine shown in my Patent No. 1,244,277, granted October 23, 1917, for improvements in wrapping machines. It therefore is deemed inadvisable to show the details of this mechanism in the present application.

In order to properly align the bands on the package or, in other words, to keep them 90 in their parallel and spaced relationship, an arm 100 is pivoted to one of the plates 76 directly over the path of travel of the nipper 72, as shown in Fig. 5, and is of such length that, as the nipper is withdrawn carrying a 95 pair of bands with it over the glue applying rolls 97 and 98, the arm 100 will drop between the bands and thus keep them properly spaced. This arm, of course, because 100 of its pivotal movement, is moved out of the path of the nipper 72 when the nipper strikes it on the forward stroke of the nipper. These parts are shown in Fig. 7 in the positions which they would occupy just after 105 the nipper 72 has moved through the opening 78 in the first plate 76, the arm 100 having dropped into substantially a vertical position between the bands L and S. The forward ends of the bands at this time lie between the two plates 76 and they are held 110 in alignment by the opposite sides of the aperture 78 and by the arm 100. The bands are supported at this time by the lower edge of the forward aperture 78 and by horizontal shoulders formed in a plate 102 (see 115 Figs. 5 and 7) which is secured to the rear wall of the glue tank 99. These shoulders are notched or cut away at points immediately under the strips of glue g on the bands but support each band at opposite sides of 120 said strip. In Fig. 7 the bands S and L are shown slightly above these shoulders for the purpose of clearness. A pin 101, projecting horizontally through the arm 100 lies at this time immediately over the bands S and L 125 and prevents any tendency of the bands to twist or get out of their proper positions. These bands thus are caused to move in a definite or predetermined path and are held accurately in proper positions for their ap- 130

lication to the package, thus insuring their correct placement on the package and the exact registry of the ends of the bands with reference to each other in the subsequent 5 folding operations.

The nipper continues its backward movement until it has delivered the two bands in the proper position on the package lying between the plates 76 at which time the 10 cam 95 operates the movable jaw 85 of the nipper to cause it to release the bands. Fig. 1 shows substantially the position of the bands on the package at this time. During the latter part of the movement of the nipper, a presser head 110, carrying a yieldingly supported presser plate 111 in which a horizontal series of rolls 112 are mounted, descends between the plates 76 on to the top of the package which is supported over 15 the elevator 50. This presser member is mounted on the upper ends of a pair of guide rods 114 (see Fig. 11) which slide in vertical guideways formed in the machine frame, and is operated by a cam 115 through connections including a link 116 and a lever 117. The series of rolls 112 which form the package engaging portion of this member are brought down on top of the bands L and S as soon as they are positioned on the package by the nipper 72 and just prior to the opening movement of the nipper so that they clamp the two bands in their proper positions on the package before or at substantially the same time that 20 the bands are released by the nipper. The U-shaped elevator 50 immediately begins its upward movement, the yielding arm of this elevator finding its proper position on the side of the package in the manner above 25 described, and the elevator and presser member then rise simultaneously to the position in which they are shown in Fig. 5, carrying the package with them. The upward movement of the package brings the projecting 30 portions of the bands against the upper edges of the apertures 78 in the two plates 76 and folds these projecting portions over the folds of the wrapper at the opposite ends of the package.

35 As soon as the package has arrived in the position in which it is shown in Fig. 5, a bottom folder 120 advances under the package into the space between the arms of the elevator 50. This folder carries a series of 40 rolls 121 which form its package engaging face and operate on the rear depending flaps of the two bands to fold them against the bottom of the package, leaving the package in the condition in which it is shown in 45 Fig. 2. This folder is mounted fast on a horizontal slide 122, Fig. 5, from which an arm 123 depends, and it is operated by a cam 124 on the shaft 4 which rocks a lever 125, the upper end of this lever being 50 connected by an adjustable link 126 to the

member 128. As soon as this folder has moved into the position in which it is shown in Fig. 5, a plunger 128, formed on a slide 134 lying parallel to and just above the slide 122, engages the rear face of the package and starts the package ahead, the folder 120 moving in unison with the plunger 128. Inasmuch as the package is now supported on the folder 120, the elevator 50 is now free to descend in readiness to receive another package. The U-shaped form of the elevator also permits the nipper 72 to advance while the elevator is in its uppermost position through the space between the elevator arms in readiness to deliver another 55 80 pair of bands.

A cam 130 on the shaft 4 operates a lever 131 which is connected by means of a link 132 to a lug 133 projecting from the bottom of the slide 134 on which the plunger 128 is mounted and gives this plunger its operative movement. The members 120 and 128 continue their forward movement in unison until the parts have reached substantially the positions in which they are 90 shown in Fig. 6 at which time the folder 120 stops while the plunger 128 continues to move forward, thus pushing the package on to a series of rolls 137 mounted on a stationary plate 136 and forming a stationary 95 folder. These rolls 137 fold the forward depending ends of the bands against the bottom of the package and over the ends of the bands that have already been folded by the rolls 121, leaving the package in the 100 condition in which it is shown in Fig. 3. Preferably the two bands are glued throughout their entire length so that they will be firmly secured to the package and their ends will be secured to each other.

The package is advanced far enough by the plunger 128 so that one of a series of bars 139, carried by a pair of chains 138 which lie on opposite sides of the path of movement of the packages, engages the rear face of the package as soon as the plunger 128 withdraws and continues the advancing movement of the package. The parts 126 and 120, of course, immediately withdraw to their initial positions in readiness to operate on the next succeeding package. It will be readily understood that, by making the package engaging portions of the presser member 110 and the folder 120 in the form of a series of rolls, as above described, the 110 movement of the package relatively to these parts cannot wrinkle up the wrapper or the bands since the rolls will travel with the 115 parts of the package on which they bear.

The chains 138 operate through the bars 125 139 to force the packages over a supporting plate 140 and under a series of yieldingly mounted presser plates 141 carried by a removable plate 142. The plate 140 preferably is covered with a strip of canvas or 130

some similar material which loosely encircles the member 140 so that it can slip on this member under the drag of the packages while at the same time coöperating with the 5 presser plates 141 to hold the bands firmly in their folded positions while the glue is drying. After the packages pass out from under the presser plates 141 they are carried by the chains 138 on to a conveyer 10 belt 144 which is supported on rotatable pulleys. Preferably the chains 138 are given a step by step movement, by mechanism shown in my parent application above designated.

While I have herein shown and described 15 the best embodiment of the invention of which I am at present aware, it is obvious that this embodiment may be modified within the skill of the mechanic and the discretion of the designer without departing from 20 the spirit or scope of the invention.

What is claimed as new, is:

1. In a machine of the character described, the combination of a vertically movable U-shaped elevator each arm of which is shoul- 25 dered near its upper end to engage the op- posite side faces and the bottom of a pack- age, said arms being supported for relative yielding movement to enable them to accom- modate packages of different widths, means 30 for delivering packages to said elevator one at a time, band feeding mechanism operative to position a band in the path of movement of said package while it is on said elevator, and means for folding said band around 35 said package including a folder movable into the space between the arms of said elevator.

2. In a machine of the character described, the combination with a vertically movable 40 plunger, means for presenting articles one at a time to said plunger, a presser device movable into engagement with the article pre- sented to said plunger to press said article against said plunger and thereafter movable with said plunger to transfer the article, 45 band feeding mechanism operative to inter- pose a band between said article and said presser device, said presser device comprising a series of yieldingly supported rolls 50 forming its package engaging surface, a pusher operative at right angles to the move- ment of said plunger to remove the package from said plunger and presser device, and folders each having a series of rolls forming 55 their package engaging surfaces and opera- tive to fold the band about the package.

3. In a machine of the character described, the combination with devices for affixing 60 bands to packages, of means for advancing packages one at a time for the banding op- eration, a reciprocating nipper, means for operating said nipper to cause it to position a pair of bands in the path of each package, means for positioning bands one pair at a 65 time so that said nipper can grasp them,

and means coöperating with the nipper to aline each pair of bands in the path of the packages.

4. In a machine of the character described, the combination with devices for affixing 70 bands to packages, of means for advancing packages one at a time for the banding operation, a reciprocating nipper, means for operating said nipper to cause it to position a pair of bands in the path of each package, 75 means for positioning bands one pair at a time so that said nipper can grasp them, and means coöperating with the nipper to aline each pair of bands in the path of the packages including a device normally positioned 80 in the path of the nipper and constructed and arranged to guide the bands but mounted to be moved by the nipper out of its path as it advances and movable into band guiding position again when the nip- 85 per retires.

5. In a machine of the character described, the combination with devices for affixing 90 bands to packages, of means for advancing packages one at a time for the banding op- eration, a reciprocating nipper, means for operating said nipper to cause it to position a pair of bands in the path of each package, means for positioning bands one pair 95 at a time so that said nipper can grasp them, means coöperating with the nipper to aline each pair of bands in the path of the packages, and means for applying adhesive 100 material to the bands while they are being advanced to the path of the packages.

6. In a machine of the character described, the combination with means for affixing bands to packages, of means for advancing 105 packages one at a time for the banding op- eration, means operative to position a pair of bands in the path of each package, and means coöperating with said advancing means to aline each pair of bands properly in said path.

7. In a machine of the character described, the combination with means for affixing 110 bands to packages, of means for advancing bands to packages one at a time for the banding operation, means constructed and arranged to reciprocate across the path of the packages 115 and operative to position a pair of bands in the path of each package, means for position- ing bands one pair at a time for the en- gagement therewith of said reciprocating means, and means coöperating with said re- ciprocating means to aline said bands par- 120 allel to each other in the path of the pack- ages.

8. In a machine of the character described, the combination with means for affixing 125 bands to packages, of means for advancing bands to packages one at a time for the banding operation, means operative to position a pair of bands in the path of each package, glue applying rolls over which the bands are 130

moved by said band positioning means, and means operative to guide said bands into contact with said rolls and to keep the bands properly aligned.

- 5 9. In a machine of the character described, the combination with means for affixing bands to packages, of mechanism operative to advance packages one at a time for the banding operation, a reciprocating nipper, mechanism for operating said nipper to cause it to position a pair of bands in the path of each package, means for positioning bands one

pair at a time to enable said nipper to grasp them, a pair of glue applying rolls over which the bands are fed by said nipper, and 15 guiding means constructed and arranged to guide said bands in predetermined paths, said guiding means including a device having a part normally resting in the path of said nipper and being mounted to be moved 20 out of said path by said nipper.

In testimony whereof I have signed my name to this specification.

HARRY Y. ARMSTRONG.
